EARTH ANCHOR

Jasper Blackburn, Webster Groves, Mo.

Application May 28, 1930, Serial No. 456,383

4 Claims. (Cl. 189—92)

My invention relates to improvements in earth anchors, and has for its primary object an earth anchor provided with a plurality of flukes which can be expanded simultaneously in radial directions so that the flukes will imbed themselves in solid ground thereby preventing the pulling up of the anchor.

A further object is to construct an earth anchor which is provided with a plurality of radially expansible flukes, the flukes being separately mounted on a base.

A still further object is to construct an earth anchor having a plurality of radially movable flukes, the flukes being so constructed that they can be readily placed upon a base and retained in position thereon without the necessity of extraneous fastening means.

A still further object is to construct an earth anchor having a plurality of radially movable flukes, the flukes being so constructed as to limit their outward movement.

In the drawings, Fig. 1 is a top plan view of the uppermost fluke employed.

Fig. 2 is a top plan view of the second fluke.

Fig. 3 is a top plan view of the third fluke.

Fig. 4 is a top plan view of still another fluke.

Fig. 5 is a top plan view of the base.

Fig. 6 is a side elevation of the same.

Fig. 7 is an enlarged perspective view showing the central boss.

Fig. 8 is a cross-sectional view, taken substantially along the line 8—8 of Fig. 1.

Fig. 9 is a front view of one of the links employed in expanding the flukes.

Fig. 10 is a side elevation of the same.

Fig. 11 is a cross-sectional view, taken substantially along the lines 11—11 of Fig. 1.

Fig. 12 is a perspective view of the fluke shown in Fig. 1.

In the construction of my device, I employ a base 11 which is provided with a central boss 12. This boss is provided with an opening 13 extending vertically centrally therethrough. This opening is for the reception of an anchor rod.

The anchor rod may be secured in the opening 13 in any well known manner either by being screw threaded therein, riveted therein or welded.

Referring more particularly to Fig. 7 of the drawings, it will be noted that the central boss 12 is preferably substantially rectangular in plan view, so as to prevent rotation of the flukes relative thereto, as will be more clearly hereinafter explained, said boss being longer in one direction than in the other. The pairs of parallel vertical faces of the boss are indicated at 17—18

and 22—22 respectively, and flanges 15—15 are provided along the top edges of the parallel faces 22—22. Adjacent these flanges and therebelow the sides are recessed or undercut at 16—16 on the faces 22—22, and similar recesses 19—19 are provided parallel to and below the recesses 16—16. The recesses 16—16 open onto the adjacent face 17, and the other recesses open onto the parallel face 18.

The faces 17—18 are provided with similar cutouts or recesses 20 and 21, the former opening onto the face 22 and the latter opening onto the face 22 opposed to the first face 22, the recesses 20 and 21 being parallel to one another, but vertically spaced apart. It will be noted that the recesses 16, 19, 20 and 21, do not extend the full length of the faces but only for a portion thereof, and each has an end wall that forms a closed end for the recess and forms an abutment stop to co-operate with the flukes, as will be hereinafter described.

The base 11 is also provided with upwardly extending projections 23—24—25 and 26, these projections serving as supports for certain of the flukes as will be hereinafter described. Resting on the base 11 is a fluke 27 which fluke is provided with a cutaway portion 28 which forms a slot so as to permit the fluke to be placed over the narrower portion of the central boss 12, the edges of the cutaway portion 28 resting against the faces 17 and 18 of the central boss. The ends of the fluke 27 are provided with inturned projections 29 extending toward one another which projections are adapted to enter the recesses or cutaway portions 21 of the central projection and abut the closed end thereof and thus limit the outward movement of the fluke 27. The fluke 27 is also provided with a socket 30 which is designed to receive the end 31 of an operating link, the opposite ends 33 of these links being secured in a common spider provided with arms corresponding to the number of flukes employed in connection with the anchor, the links being of identical construction, but of different lengths and will bear the same reference number throughout the specification.

Resting on top of the fluke 27 is a fluke 35. This fluke is provided with a cutaway portion 36 identical in construction with cutaway portion 28 and with similar inturned ends 37. These inturned ends are adapted to pass into the cutaway portions 20 of the central boss so that the outward movement of the fluke 35 will be limited. The fluke 35 is also provided with a socket 38 which serves the same purpose as the socket 30.

The fluke 35 in addition to resting on the fluke 27 is also supported by the projections 25 and 26 which keeps it from tilting.

Resting on the fluke 35 is a fluke 39 which is provided with its cutaway portion 40. One side of this cutaway portion 40 is recessed as indicated by the numeral 41 and directly opposite this recess is an inclined or beveled portion 42 thinnest at its free edge. This permits the fluke 10 to be shifted and tilted sufficiently to be inserted in position and passed underneath the flanges 15. The fluke 39 is also provided with the inturned ends 43 adapted to ride in and abut the ends of the recesses 19, thus limiting the outward 15 movement of the fluke 39. The fluke 39 also rests on the projections 24 so as to prevent it from tilting when expanded.

Resting on the fluke 39 is a fluke 44 which fluke is provided with its cutaway portion 45. 20 This cutaway portion is provided along one edge with a recess 46 and on the opposite edge with the inclined portion 47 serving the same purpose as the recessed and inclined portions 41 and 42 of the fluke 39. The fluke 44 is also provided 25 with the inturned ends 48 which are adapted to enter or ride into the recesses 16 and thus limit the outward movement of the fluke adjacent the inturned ends 48 and 44. In addition, I have provided upwardly projecting portions 49 on this 30 fluke which ride underneath the flanges 15 to abut against the latter when the fluke is tilted slightly thus preventing the inner ends of the fluke from tipping upward when the fluke is in expanded position. The fluke 44 is further supported by the projection 23 formed on the base 11. The fluke 44 is also provided with a socket 35 50 for the reception of a link, the opposite end of the link being attached or supported in the spider.

40 The base 11 is provided with an opening 51 which opening is in alignment with the openings 52-53-54 and 55 formed respectively in the flukes 44-39-35 and 27. The purpose of these 45 openings is to permit the insertion of a wire or other securing means to prevent the accidental expansion of the flukes either during shipping or while being inserted into the earth preparatory to expanding. This securing means, however, is of such a nature that after the anchor has been 50 inserted in the ground it can be readily ruptured and permit the expansion of the flukes, but still at the same time has sufficient tenacity to hold the flukes in collapsed position under ordinary 55 circumstances.

55 The manner of installing my anchor is as follows:—

The first step is to bore a hole in the ground of approximately the same diameter as the diameter of the base, it being understood of course, 60 that this hole is slightly larger than the anchor and is bored at any desired angle. The anchor is then inserted and by means of a tamping bar the spider is struck a succession of blows forcing the spider downward on the rod 14 toward 65 the base. This movement of the spider causes the links to force the various flukes outward and into the solid earth surrounding the hole previously bored. The tamping bar is then removed

and the hole filled up with any suitable material.

It is understood, of course, that the flukes may be held in collapsed position by means of a lead rivet, by means of a thin wire or by means of a cord. When the flukes are so secured, the downward movement of the spider and the consequent expansion of the flukes will rupture this holding means and permit the flukes to expand. If a bolt or extremely heavy wire is used to hold the flukes in collapsed position, this is first removed before the anchor is lowered into the hole.

86 It is also to be understood, of course, that the upper end of the anchor rod is provided with an eye so that one end of a guy wire or cable can be secured thereto.

88 Having fully described my invention, what I claim is:—

1. An earth anchor comprising a base, a central boss thereon having a plurality of pairs of grooves in its sides, a plurality of flukes mounted for movement on said base, means for moving said flukes outward radially of said base, and means carried by each of said flukes and adapted to enter one of said pairs of grooves thereby engaging with said central boss and for individually limiting the outward movement of each of said flukes independently of the other flukes.

96 2. An earth anchor comprising a base, a polygonal central boss thereon, each face of said polygon having a pair of grooves in different planes therein, a rod carried by said boss and projecting therefrom, a spider slidably mounted on said rod, a plurality of flukes slidably mounted on said base and each slotted to non-rotatably receive said boss, a boss carried by each of said flukes, links pivotally carried at their ends by said last mentioned bosses and said spider whereby said flukes are moved outwardly when said spider is moved toward said base, means carried by each of said flukes and adapted for engagement with one of said pairs of grooves of said central boss for limiting the outward movement of said flukes, and laterally extending flanges formed on said central boss at its upper end for retaining said flukes on said base.

105 3. An earth anchor comprising a base having a central boss extending thereabove, said boss having grooves in its sides, a plurality of radially movable flukes on said base and having slots extending therethrough to receive said boss and be non-rotatable thereon, and inturned projections carried by each of said flukes at one end only of said slots to enter said grooves and abut the end walls of the latter to limit further outward movement of the flukes.

112 4. An earth anchor comprising a base, a central boss thereon and having a plurality of vertically spaced grooves in its side walls, a plurality of flukes superimposed above one another and slidably mounted on said base, each in one of the 118 planes of said vertically spaced grooves, each of said flukes having a slot therein to slidably receive said boss and having inturned projections at one end of said slots, whereby said projections will engage in said grooves and abut the ends of the latter to limit further outward movement of said flukes.

125 JASPER BLACKBURN.
